WALL MOUNTED DEVICE FOR SUPPORTING ARTICLES DRAPED THEREON

George W. Turner, Youngstown, and Howard F. Herman,
North Jackson, Ohio

Application June 29, 1955, Serial No. 36,756

Term of patent 7 years

(Cl. D33—8)

We claim:

The ornamental design for a wall mounted device for supporting articles draped thereon, substantially as shown.
